UNITED STATES PATENT OFFICE.

JOSEPH P. BURT, OF ELDORADO, KANSAS.

TUG-ROPE HOLDER.

1,274,984.

Specification of Letters Patent.

Patented Aug. 6, 1918.

Application filed April 26, 1918. Serial No. 230,994.

To all whom it may concern:

Be it known that I, JOSEPH P. BURT, a citizen of the United States, residing at Eldorado, in the county of Butler and State of

5 Kansas, have invented certain new and useful Improvements in Tug-Rope Holders, of which the following is a specification, reference being had therein to the accompanying drawing.

10 This invention comprises a tug-rope holder. While it is of general application, it is especially useful in connection with drilling machines and the like.

In machines of this character, there is provided a driving connection between a band-wheel and a tug-wheel. The band-wheel is driven directly from an engine or other source of power, and the tug-wheel is connected by a tug-rope or other driving connection with the band-wheel, and is generally used only when withdrawing the tools from the hole. When the tug-wheel is not in use, the rope or ropes which usually connect it to the band-wheel are removed from the 25 band-wheel and allowed to rest in suitable grooves on the band-wheel. This causes a drag on the latter which acts in the nature of a brake, thus increasing the demand on the engine and wasting fuel, in addition to 30 wearing grooves in the band-wheel, which is continually rotating, and also causing considerable wear on the rope.

By the present invention there is contemplated the provision of simple and effective 35 means for holding the tug-rope or other driving connection out of engagement with the band-wheel when it is not connected with the tug-wheel; the mounting of such means, preferably upon an extended portion 40 of the shaft upon which the band-wheel is mounted, so as to occupy but small space and be readily accessible; and which means will obviate the difficulties above enumerated. Other objects and advantages will in part 45 be apparent and in part be brought out more clearly in the description which follows.

Drawings illustrating an embodiment of the invention are hereto appended, and in which the following views are shown.

50 Figure 1 is a view in side elevation showing the band-wheel and tug-wheel in driving connection and the holder arranged out of engagement with the driving connection;

Fig. 2 is a similar view showing these 55 wheels disconnected and the holder arranged

in operative position to hold the driving connection out of contact with the band-wheel;

Fig. 3 is a view in fragmentary front elevation of the band-wheel and showing in detail the relative position of the ropes and rope-holder shown in Fig. 2;

Fig. 4 is a fragmentary detail view in perspective of a portion of the rope-holder; and

Fig. 5 is a side elevation of a part of the 65 device.

Referring specifically to the drawings, the numeral 1 represents a band-wheel mounted on an axle 1' and suitably driven, as by a belt 2, from a source of power (not shown). 70 Associated with this band-wheel is a drum 3 having grooves 4 in which there is adapted to be seated ropes, or other driving connection, 5 which connect the band-wheel with a tug-wheel 6. All of this is well-known 75 construction. The device which constitutes the present invention includes split-bearing members 7, each of which carries a flange 8, the members being suitably secured together around the shaft 1 to permit rotation 80 of the flanges and bearings on the shaft.

Secured to one of the flanges are straps or supports 9 in spaced-apart relation, and on the outer end of each strap there is an angulated extension 10 formed with notches 85 11 spaced apart and arranged to receive and retain the ropes or other driving connection 5 when the holder has been moved into the position shown in Fig. 2. These angulated extensions are connected by longitudinally-extending straps or braces 12, the whole constituting a fan-shaped, skeleton holder mounted upon one of the flanges 8.

Means are provided for moving the holder into and out of operative engagement with 95 the rope or ropes and, as here shown, such means comprise an arm 13 mounted on the other flange 8 and to the end of which there is pivotally secured a lever 14 having at its opposite end a handle 15 and intermediate 100 its ends stops 16 adapted to engage an upright or support 17.

Means are also provided for retaining the holder in inoperative position, and to this end a brace or strap 18 is secured to the 105 outer end of the supports 9, and upon this brace there is a lug 19 which is adapted to straddle the lever 14 when the device is in the position shown in Fig. 1.

An arm 20, secured to one of the flanges 110

opposite the holder and carrying at its free end a counterweight 21, constitutes a means for retaining the holder normally in the position shown in Fig. 2 and will hold it 5 in such position, regardless of whether or not the inner stop 16 is in engagement with the upright 17.

When in the position shown in Fig. 1, the outer stop 16 is in engagement with a portion 10 of the upright 17, and the lug 19 straddles a portion of the lever 14, thus retaining the holder out of engagement with the ropes. When the stop has been released and the lever actuated to the position shown in Fig. 15 2, the holder is moved to a position between the drum 3, and the ropes or driving connection 5 are retained in the notches 11 on the holder arms and out of engagement with the drum.

20 From the foregoing, it will be apparent that there is provided by the instrumentalities just described simple and efficient means for performing the functions and accomplishing the objects hereinbefore set forth.

25 While the invention has been illustrated in the embodiment set forth, it will be understood that I do not desire to be limited to the precise form of this disclosure; as many changes in the construction and arrangement of the parts may be made without departing from the scope of the invention, as 30 set forth in the claims.

What I claim is:

1. A tug-rope holder comprising in com-

bination with a band-wheel and its supporting axle; a bearing-member mounted on the axle; supporting-members mounted on said bearing-member, their free ends being in spaced relation; angulated extensions on said supporting-members; a longitudinally 35 extending strap connecting the angulated extensions; an operating lever for moving the support into and out of engagement with the rope; and means for positively retaining the support in both positions.

2. A tug-rope holder comprising in combination with a band-wheel and its supporting axle; a bearing-member mounted on the axle; supporting-members mounted, at one end, on said bearing-member, their free ends being in spaced relation; angulated extensions on said supporting-members and each provided with a rope-receiving notch; a longitudinally extending strap connecting the angulated extensions; a weighted member 50 disposed on the bearing opposite the supporting members; an operating lever for moving the support into and out of engagement with the rope; means for positively retaining the support in both positions; and 55 means carried on one of the members and adapted to engage the operating lever to maintain the support at the limit of its movement out of engagement with the rope.

In testimony whereof, I have hereunto affixed my signature.

JOSEPH P. BURT.
